BY S. Schoffield, ATTY.

UNITED STATES PATENT OFFICE.

HENRY E. HUGHES, OF PAWTUCKET, RHODE ISLAND.

DESIGN FOR A SPINDLE-LOCK.

SPECIFICATION forming part of Design No. 30,793, dated May 16, 1899.

Application filed March 15, 1899. Serial No. 709,209. Term of patent 14 years.

To all whom it may concern:

Be it known that I, HENRY E. HUGHES, a citizen of the United States, residing at Pawtucket, in the county of Providence and State 5 of Rhode Island, have invented and produced a new and original Design for Locks for Spinning-Spindles, of which the following is a specification, reference being had to the accompanying drawings, forming a part thereof.

10 In the accompanying drawings, Figure 1 represents a side elevation of a spindle-lock of my new design. Fig. 2 represents a top view of the spindle-lock. Fig. 3 represents a perspective view.

15 As shown in the drawings, my design for a

spindle-lock consists of the circularly-curved horizontal portion *a*, the upright portion *b*, and the inwardly-projecting portion *c*, extending at about a right angle to the upright portion *b* to form the engaging lip of the lock. 20

Having described my invention, what I claim as new, and desire to secure by Letters Patent, is—

The design for a spindle-lock as herein shown and described.

HENRY E. HUGHES.
